PIO NARCISO PECCI, OF PATERSON, NEW JERSEY, ASSIGNOR OF ONE-HALF TO LEON LEMIEUX,
OF PATERSON, NEW JERSEY.

AUTOMATIC BLOCK-SIGNAL FOR TROLLEY SYSTEMS.

No. 926,437.

Specification of Letters Patent.

Patented June 29, 1909.

Application filed June 4, 1908. Serial No. 436,570.

To all whom it may concern:

Be it known that I, PIO NARCISO PECCI, a citizen of the United States, residing in Paterson, Passaic county, New Jersey, have invented a certain new and useful Improvement 5 in Automatic Block-Signals for Trolley Systems; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates to automatically actuated signal systems and particularly to such systems as designed for use in connection with trolley or other railways wherein parts thereof consist of sections of single 20 track and means are necessary whereby a car or train about to enter a single-track section may be advised whether or not a car or train is entering said section in the opposite direction.

25 In my system I provide a safety and a danger signal device at each end of each single-track section; an electrically actuated motor (one for cars entering each single-track section in one direction and another 30 for cars entering said section in the other direction), each of which motors, when actuated from a car corresponding thereto, sets the danger signal at the far end of said section and the safety signal at the near end of 35 the same, the former to warn a car entering the section from the far end and the latter to assure the first-mentioned car that the way is clear; and two devices whereby each motor is electrically controlled by a car passing 40 through the single-track section, the one being located at the near end of said section and the other at the far end, and the former serving to close a circuit containing the motor and thereby cause the motor to set the 45 signals appertaining thereto and the latter serving to close another circuit containing the motor and thereby reverse the motor and consequently reverse the signals—in the case where the signals are electric lights, break 50 the lighting circuit and put out the lights.

In carrying out my invention, I have contemplated so constructing the system as to make the same entirely automatic and reliable and to use a part of the current which

may be employed for propelling cars or 55 trains.

My invention will be found fully illustrated in the accompanying drawings, wherein,

Figure 1 is a diagrammatic view of a trolley railway having single-track sections and 60 of my system; Fig. 2 is a front view, certain parts being broken away and others shown in section, of an apparatus comprising the safety and danger signal means which is located near each end of each single-track section and the motor which controls said 65 safety signal means and the danger signal means which is comprised in a similar apparatus at the (relatively) far end of said track-section, together with a part of the 70 necessary wiring; Fig. 3 is a vertical sectional view on Fig. 2 taken a little to the right of the center of said figure and looking toward the left therein; Fig. 4 is a horizontal sectional view taken on Fig. 2 just above 75 a certain bell-crank lever controlled by the motor; Fig. 5 is an underneath plan view of the upper casing shown in Figs. 2, 3 and 4, showing the wiring on the bottom of said casing; Fig. 6 shows a trolley wire, a trolley- 80 pole and the device whereby the trolley-pole is made to make and break the circuits containing the motors; Fig. 7 and Fig. 8 are sectional details of parts shown in Figs. 2, 3 and 4; and, Fig. 9 is a diagram of a part of the 85 lighting circuit.

a in Fig. 1 designates the trolley wire, and *b* the railway double track-sections and *c* the railway single-track sections.

d, Fig. 6, is the trolley pole, comprising the 90 wheel *e*, and *f*, Figs. 1 and 6, the devices whereby, when actuated by the wheel *e*, the circuits containing the motors are established; one such device *f* is supported by the guy-wire *g* or the like in proximity to each 95 branch of the trolley-wire *a* where the same adjoin the single-track sections, so that a car as it enters a single-track section will actuate one such device *f* and as it leaves said section will actuate another. 100

The devices *f* may be described as follows: *h* is a box containing an electro-magnet *i* and an armature *j* therefor, said magnet and armature being connected by the wires *k* and *l*, respectively, with the binding posts *m* and *n* and being so arranged that in the normal position of the armature it hangs pendent 105 out of electrical contact with the magnet but

when moved against the magnet the circuit containing them will cause the magnet to retain the armature in contact therewith so long as said circuit is unbroken; when it is broken, the armature falls to its normal position. A circuit closer of this type insures maintenance of the circuit so far as such circuit closer is concerned once it barely effects a closing of the circuit, and is of great value in a system of this kind in order to make it automatic and reliable.

Adjoining each end of each single-track section is placed the apparatus illustrated in Figs. 2, 3, 4, 5, 7, 8 and 9, which may be described as follows: *p* and *q* are an upper and a lower box, the former containing signals operated from the far end of a single track section and a motor for controlling the corresponding signals in the upper box of a similar apparatus at said far end of said track-section and the latter containing a signal controlled by said motor; each upper and lower box has at both ends openings *r* which may be glazed with different colored glass *s*, say red for the upper box and white for the lower. Besides a movable signal to be described, the upper box contains a series of incandescent lamps *t*; the lower box contains, as its signal device, a series of similar lamps *u*.

A wire *v* carrying the lighting current extends from the trolley wire *a* into each box *p* where it is divided into the branches *v'* and *v''*, the former containing the lamps of box *p* and the latter the lamps of box *q* for the apparatus at the far end of the track-section; said branches are grounded at *w* and *x*, respectively. The terminals for the wires *v*, *v'* and *v''* in box *p*, marked *y*, *y'* and *y''* in Fig. 1, are mounted separately from each other on an insulating plate *z* and each consists of a blade 1 fixed to plate *z* by the binding post 2 and a pivoted blade 3 held against the blade 1 by a spring 4, the free ends of the blades, which stand horizontally, being flared so that when a circuit closing metallic member (to be described) is moved toward said blades 1 and 3 it will enter between them and form a good electric contact. Each branch *v'* and *v''*, in the portion thereof including the lamps, is itself divided as shown in Fig. 9 and contains some of the lamps in each division, the idea being thereby to prevent the cutting out of all the lamps should one burn out.

The circuit containing the lamps in the upper box and the lamps in the lower box of the corresponding apparatus at the far end of the track-section is closed by a metallic blade 5, the current from wire *v* being thus divided and passing into the wires *v'* and *v''*; this blade is of course in the box at the far end of the track-section and it and the parts controlling it are precise duplicates of the corresponding parts shown in the drawings. It is carried by one end of a cross-arm 6 in turn carried by the sliding core 7 alternately

controlled by the electro-magnets 8, aligned with each other; it further carries a T 9 in which are arranged the aligned rods 10 moving in the insulated guides 11. On the core 7 are adjustable stop collars 11' adapted to abut against the respective magnets to limit the throw of the core. A bridge 12 is carried by the magnets and on this is fixed the block 13 carrying, insulated therefrom, the bearing 14 for a bell-crank lever 15 one arm 15' of which is forked and receives a roller 16 on the cross-arm 6; the other arm 15'' of said lever 15 projects under a semaphore-lever 17 which is normally retained in the horizontal or "danger" position by a weight 18 thereon and which is fulcrumed in a bracket 19 depending from a block 20 carried by another bracket 21 which is carried by the bridge 12. An anti-friction roller 22 may be arranged on the semaphore-lever to take the contact of the bell-crank lever 15. On the block 20 is arranged a bracket 23 in which is fulcrumed a cut-out lever 24 adapted at one end to engage the metallic clip 25 and at the other end an adjusting screw 26, the movement of said cut-out lever into contact with the clip being effected by the semaphore-lever (which lies in the same vertical plane) when the latter has its inner end thrown up by the bell-crank-lever 15, and the movement of said cut-out lever in the other direction being effected upon the return movement of the semaphore-lever through a hook 27 engaged with the semaphore-lever and guided in the fixed sleeve 28 and a spring 29 connecting said hook with an adjusting screw 30 on the cut-out lever; the end of the semaphore-lever carries insulation 31 which affords the medium of contact with the cut-out lever.

Opposite the insulating plate *z* is arranged another insulating plate 32 to which are attached, on one side thereof by the screw 33 and binding-post 34, the flaring horizontal blades 33' and 33'', and, on the other side 110 thereof, by the screw 35 and binding post 36, the similar flaring horizontal blades 35'; the blades 33' and 33'' are adapted to be electrically separated from each other by an insulating wedge 37 carried by the blade 5, 115 and the blades 35' and 35'' are adapted to be electrically separated from each other by the insulating wedge 38 carried by the rod 10. The blades 33' and 35' carry screws 39 affording means for electrical contact with 120 their complementary blades.

It will be observed, on reference to Fig. 2, that each motor comprises two elements, the magnets 8, the right hand one of which on Fig. 4 closes the lighting circuit and the other of which breaks the lighting circuit. Each motor is at the far end of the single-track section relatively to a car entering said section; the element 8 for closing the lighting circuit is contained in a circuit com-

prising a wire 40 connecting the trolley wire with the binding post *n*, magnet *i*, armature *j*, a wire 41 extending from binding post *m* to a binding post 42 on the bottom of box *p*, said binding post 42, a wire 43 extending from 42 to the screw 35, through the blades 35', 35², binding post 36, a wire 44, 25, 24, 23, the wire 45, right-hand magnet 8, a wire 46, a binding post 47, wire *v'* to ground *w*. The element 8 for breaking the lighting circuit is contained in a circuit comprising a wire 48 connecting the trolley wire with the binding post *n* of the device *h* at the far end of the track-section, a wire 49 extending from binding post *m* to binding post 50 in box *p*, said binding post, a wire 51 leading to said element 8 (left hand magnet in Fig. 4), a wire 52, 34, 33², 39, 33', 33, a wire 53, 47, *v'* to ground *w*.

Assuming that a car is about to enter a single-track section and that the signal apparatus at that point shows the way clear, its trolley wheel engages the armature *j* and moves the same against the magnet *i*, where it will be automatically held as soon as contact therewith is effected. At this time the motor in the signal apparatus at the far end of said track-section stands with its parts in the left instead of the right-hand position, as in Fig. 2, so that, the lighting circuit being broken, the lights in the adjoining box *q* and in the remote box *p* are extinguished and the motor circuit for the left-hand magnet is broken by the insulating wedge 37 separating the blades 33' and 33²; but the circuit containing the right-hand magnet is complete at the blades 35', so that, once the circuit is completed between *i* and *j*, the right-hand magnet draws the core 7 quickly to the right, thus shifting lever 15 which allows the weighted arm of the semaphore lever 17 to drop, bringing the latter into the "danger" position; at the same time the lighting circuit is established, lighting the lamps in box *p* at the far end of the track-section and in box *q* at the near end thereof. When this movement of the parts takes place, the right-hand magnet 8 cuts itself out of circuit at two points, viz., by insulating wedge 38 separating the blades 35' and by the semaphore-lever, through hook 37 and spring 29, pulling lever 24 away from clip 25.

When the car has passed through the single-track section and reaches the device *h* at the far end of the same, the trolley-wheel closes the circuit containing the left-hand magnet 8, which circuit has been previously closed at blades 33', 33², by the withdrawal of wedge 37 from between them; left-hand magnet 8 now reverses the movement of core 7 and the other moving parts controlled thereby, putting out the lights and causing lever 15 to move the semaphore-lever to "safety." At the same time,

magnet 8 cuts itself out by forcing wedge 37 between blades 33', 33², while it closes the circuit of the other magnet 8 by withdrawing wedge 38 from between blades 35', 35².

In view of the foregoing it will be seen that according to my system a passing car operates thereon at one point, *i. e.*, where it enters a single-track section, to cause the motor to operate in one direction, the motor then automatically reversing the current influence on itself, and then operates, *i. e.*, where it leaves said track-section, to cause the motor to operate in the other direction, the motor again automatically reversing the current influence on itself. This, as shown, is accomplished by providing the motor with two reversely acting magnets each of which is in a separate division of the circuit (*i. e.*, from the trolley wire through the system of circuit elements containing either magnet 8 to ground), by providing means for closing each division by a passing vehicle and by providing means whereby, when either magnet is actuated, it cuts itself out of circuit and establishes the other magnet in circuit; I do not wish, however, to be limited to the precise construction just described for accomplishing the operations mentioned. It may be added that my reason for providing two cut-outs (viz., 24 and 38) for the right-hand magnet is that, in order to insure the setting of the signals, a heavy pressure from the trolley wire is required in view of the comparatively considerable distance which the electric fluid has to travel from the circuit closing device at the near end of the track-section to the motor at the far end, and such heavy pressure would induce arcing if but one cut-out were used; in the case of the left-hand magnet a single cut-out will usually suffice because the motor is in that instance near the circuit closer *h* at the far end of the track-section, and the full pressure does not find access to the parts before the motor moves and cuts itself out.

The cut-out formed by the insulating wedge 38 operates to break the circuit before the cut-out lever 24 operates; this is because lever 17 does not engage the hook 27 until after the wedge 38 enters between the blades 35' and 35². The circuit is closed between blades 35' and 35² before it is closed by the cut-out lever 24, because lever 17 is not moved far enough to actuate lever 24 until the wedge 38 has withdrawn from between the blades 35' and 35².

In order that the magnets cannot counteract each other, the wedge 37 is so arranged that it breaks the circuit between 33' and 33² just before the circuit for the right-hand magnet is completed by the lever 24 engaging the clip 25.

Having thus fully described my invention what I claim as new and desire to secure by Letters Patent is:

1. The combination, with a railway, of a

- signal apparatus comprising an electric motor, means for causing the motor to move first in one direction and then in the other direction to effect the "danger" and "safety" 5 conditions of the apparatus, said motor comprising reversely actuating electro-magnets and said means comprising an electric circuit having a portion thereof divided and each division containing one of the magnets, 10 circuit closers, one in each division, adapted to be operated by a vehicle passing over the railway, and mechanism, controlled by the 65 motor, for breaking the circuit in the division thereof containing the acting magnet and establishing the circuit in the division thereof containing the inactive magnet on each actuation of the motor, substantially as 70 described.
2. The combination, with the main conductor of an electric railway, of a signal apparatus comprising an electric motor, 15 means for causing the motor to move first in one direction and then in the other to effect the "danger" and "safety" conditions of the apparatus, said means comprising other conductors leading from the main conductor, dis- 20 tanced devices, arranged each in one of said other conductors and adapted to be actuated by a passing vehicle on the railway, for closing the circuit with respect to said other conductors, and means, controlled by the motor, 25 for reversing the current influence on the motor, said last named means being operative on each closing of the circuit by one of said devices and the consequent actuation of the motor, substantially as described.
3. The combination, with a railway, of a signal apparatus comprising an electric motor, means for causing the motor to move first in one direction and then in the other direction to effect "danger" and "safety" 30 conditions of the apparatus, said means comprising an electric circuit having a portion thereof divided, distanced devices, one in each division and adapted to be actuated by a passing vehicle on the railway, for closing 35 the circuit, one part of each device being an electro-magnet and the other its armature, and means, controlled by the motor, for reversing the current influence on the motor, said last-named means being operative 40 on each closing of the circuit by one of said devices and the consequent actuation of the motor, substantially as described.
4. The combination, with a railway, of a signal apparatus comprising an electric motor, means for causing the motor to move first in one direction and then in the other direction to effect the "danger" and "safety" 45 conditions of the apparatus, said motor comprising reversely actuating electro-magnets and said means comprising an electric 50 circuit having a portion thereof divided and each division containing one of the magnets, each division having a break therein, circuit closers each electrically connected with one division at one side of, and adapted to bridge, its break and adapted to be moved 55 to the bridging or closing position by a vehicle passing over the railway, electro-magnets, one in each division, controlling the corresponding circuit closer, and mechanism, controlled by the motor, for making the 60 circuit through one division thereof and breaking it in the other and vice versa, alternately, substantially as described.
- In testimony that I claim the foregoing, I have hereunto set my hand this 1st day of 65 June, 1908.
